UNITED STATES PATENT OFFICE.

LOUIS BENNET HALL, OF LONDON, ENGLAND.

FUEL-FEED-GOVERNING DEVICE.

1,290,183.

Specification of Letters Patent. Patented Jan. 7, 1919.

Application filed June 27, 1917. Serial No. 177,237.

To all whom it may concern:

Be it known that I, LOUIS BENNET HALL, a subject of the King of England, residing in London, England, have invented certain new and useful Improvements in Fuel-Feed Governing Devices, of which the following is a full, clear, and exact description, reference being had to the accompanying drawings, forming part of this specification, in 10 which:

Figure 1 is a sectional view partially in side elevation of one form of apparatus built in accordance with my invention, and

Fig. 2 is a side elevation partially in section of a modified form of valve mechanism between the pulsator and the air column.

This invention relates to an improvement in fuel-feed governing devices for internal combustion engines, and is designed to provide a simple, cheap and efficient device which automatically governs the amount of liquid fuel pumped to the engine under varying conditions.

The device comprises a liquid fuel pump 25 actuated by variable mechanism such as shown and described in my co-pending application Serial No. 177,236, filed June 27, 1917, to vary the feed of the pump, and which mechanism is arranged to be varied 30 by a pulsating device which periodically samples the charges for the engine and periodically varies the compression of a column of air, gas or other compressible fluid in a closed chamber, and which column in turn 35 controls the variable mechanism for the pump.

The object of my invention is to reduce to a minimum the variation of pressure in the column which would be caused by the movement of the pulsator and to maintain the pressure therein at approximately the pressure of the previous stroke until the completion of the next stroke of the pulsator, or of any other predetermined portion of 45 the pulsator movement to prevent violent fluctuations of the variable mechanism for the pump. I accomplish this by placing a valve or valves between the pulsator and the column of air, and which valve or valves are 50 positively actuated at predetermined por-

tions of the stroke of the pulsator to equalize the pressure in the column and the pressure in the pulsator.

The precise nature of my invention will be best understood by reference to the accompanying drawings which will now be described, it being premised, however, that various changes may be made in the details of construction and the general arrangement of the various parts, without departing from the spirit and scope of my invention as defined in the appended claims.

Referring to the structure shown in Fig. 1, the reference characters DP designate the fuel delivery passage to the engine and OP the fuel pump. IV is an inlet valve to the pump chamber and OV is an outlet valve therefrom, opening into the fuel delivery passage. Mounted for reciprocation in the pump casing is a ram or piston R, which is arranged to be reciprocated by an eccentric E connected to a shaft which may be either the engine crank shaft or a shaft driven therefrom. The driving connections between the eccentric E and the ram R comprise a slide block S mounted in a guide SB, and pivotally connected to this slide block S and the ram R is a walking beam, which is connected at one end to the eccentric and the slide block by a pin S', the other end R' of the walking beam being connected to the ram R by means of a block V. This block V is pivoted to the end of the ram and is provided with an opening through which the end R' of the walking beam is adapted to slide. The central portion of the walking beam extends through an opening in a floating block FP, which is connected by means of a pin P, with one end of a lever X connected to a shaft Y. This shaft Y is journaled in bearings in a casing K which incloses the ram operating mechanism, and is arranged to rock in its bearings when the floating block is moved as hereinafter described along the walking beam to vary the throw of the ram R. The position of the floating block on the walking beam is arranged to be controlled by a controlling lever RR which is pivotally connected to the floating block by the pin P which connects 100

said block to the lever X. One end of this controlling lever RR is provided with a fork having pins therein which engage a groove between flanges C on a sleeve SL, which is arranged to be controlled by the pulsator as hereinafter described. The other end of the lever RR extends through a pivoted sleeve PC^o, which is supported by links AL and L. The link AL is pivotally connected 10 to the casing K at AP, while the link L is pivotally connected to a crank M' on a shaft M. This shaft M may be rocked by any suitable controlling mechanism, or may be rocked by hand through the medium of the 15 lever connections shown in Fig. 1 to adjust the position of the sleeve PC^o which constitutes a shiftable pivot for the right hand end of the controlling lever RR.

The controlling or governing mechanism 20 for the variable pump actuating mechanism just described, comprises a compensating cylinder CS which contains a column of air, gas or any other compressible fluid which will hereinafter be termed the air column. Movably mounted in the lower end of 25 this cylinder CS is a piston CP having a piston rod which extends downwardly therefrom and connected to this piston rod is the sleeve SL. Located within the sleeve SL and surrounding a hollow stem D is a spring 30 SP which is arranged to be compressed by the column of air.

The piston rod in the piston CP extends 35 downwardly in the hollow stem and has a head P^o on the end thereof. Connected to the lower end of the rod CP is a wire or cable W through which the piston may be moved downwardly by hand, if desired.

The pulsator comprises a cylinder PC having 40 a movable piston PP therein, and inclosed within a casing CC is a cam M^o, which is connected to a shaft SH. This shaft SH is arranged to be actuated by the engine to be supplied, and the cam is provided with a 45 groove which engages a roller on the connecting rod of the piston PP.

p is a pipe leading either from the atmosphere or from the intake of the engine to the interior of the casing CC and p² is a pipe 50 communicating with a pipe p and the interior of the casing K, so that the pressures in these casings will always be equal to the atmospheric pressure, or the pressure in the intake of the engine. O are intake ports 55 communicating with the interior of the casing CC and the cylinder PC, which ports are placed so that they will only be opened by the piston PP when it is at the extreme end of its stroke. Connected to the cylinder PC 60 and communicating therewith by means of a port is a valve casing having a puppet valve RV mounted therein, which is arranged to open and close communication between the cylinder PC and the pipe Q which is in com-

munication with the compensating cylinder 65 CS. The valve RV is maintained on its seat by a spring VS, held in position by a hollow nut VC. This valve is provided with a downwardly extending stem ST which extends into the casing CC. T is a tappet 70 within the casing CC which is arranged to be raised by a cam VC^o on a shaft rotatably mounted in bearings on the casing CC. This shaft is arranged to be rotated by means of gears connecting it with the shaft SH. 75

During the operation of the engine the piston PP is reciprocated, and at the lower end of each stroke the pressure in the cylinder PC is equalized with the pressure in the pipe p, and as the piston is moved upwardly 80 toward the other end of its stroke, the valve RV will be opened by its mechanism to equalize the pressure in the cylinder PC and the pressure in the compensating cylinder CS, and if there is any variation of the conditions, the piston CP in the compensating cylinder will be moved in accordance therewith. This movement of the piston CP will shift the controlling lever RR and accordingly vary the stroke of the plunger R. 90

In the device just described, the cam M^o is provided with dwells to maintain the piston CP stationary for a short period of time at both ends of its stroke, at the one end to permit the equalization of the pressure 95 within the cylinder and the pipe p and at the other end to equalize the pressure in the cylinder PC with the pressure in the compensating cylinder CS by opening the valve RV which is open when the piston PP is stationary, which will avoid the fluctuation of the piston CP except when changes in conditions occur. If this valve were omitted the piston 100 CP would be fluctuated in accordance with the pulsation of the piston PP. The cam M^o may be one which is a simple circular eccentric. Even with such a cam the fluctuations of pressure transmitted to the column in Q from PC are only those which occur during the fraction of the stroke of PP during 110 which the valve RV is open, and they are therefore much less than the whole range of the fluctuation in PC. But if it is desired to use a pulsator which is continuously moving, i. e. without dwells, I prefer to use a 115 valve structure such as shown in Fig. 2, and in which the valve RV is arranged to be moved at the end of the up stroke of the piston PP to equalize the pressure in the cylinder and an auxiliary chamber between the 120 valve RV and a second valve SV which is normally held to its seat by a spring, and to then equalize the pressure between the auxiliary chamber and the pipe Q by opening the valve SV after the valve RV has been closed. By means of a plurality of valves and an auxiliary chamber between the compensating cylinder and the pulsating cylinder

der, I am enabled to overcome the pulsations of the pulsator even when using a continuously moving piston.

In the operation of the device, the pump is continuously operated by the eccentric E and the shaft SH is also continuously rotated to operate the pulsator and its valves. The shaft M may be adjusted to adjust one end of the controlling lever RR, either automatically or by hand, while the other end of said lever is automatically adjusted by the pressure in the compensating cylinder CS to meet the various atmospheric conditions.

By the use of an arrangement such as shown and described, the device will be automatically adjusted when used in connection with engines on aeroplanes to vary the feed in accordance with the varying weight of a cubic foot of air at different altitudes, under varying conditions of pressure and temperatures thereat.

As previously stated the pipe p may be connected to any part of the engine supplying fuel therefor or may be open to the atmosphere so that the pressure within the casings CC and K will vary in accordance with the conditions under which the engine is working. In my broader claims when referring to the fuel supply for the engine I intend to cover a supply which is either in direct communication with the atmosphere or the intake to the engine.

The advantages of my invention result from the provision of means for periodically opening communication between the compensating or governor cylinder and the pulsator or pressure supply device for the governor in order to vary the pressure in the governor in accordance with the engine conditions, without causing the mechanism controlled by the governor to be fluctuated by the movement of the pulsator or pressure supply device.

I claim:

1. In a fuel-feed governing device, a liquid fuel pump, variable actuating mechanism for the pump, a pressure actuated governor for said mechanism, a pressure supply device for the governor, and means for periodically opening communication between the governor and the pressure supply device, substantially as described.

2. In a fuel-feed governing device, a liquid fuel pump, variable actuating mechanism for the pump, a pressure actuated governor for said mechanism, a pressure supply device for the governor, communications between said pressure supply device for the governor and the fuel supply for the engine, and means for periodically opening communication between the governor and the pressure supply device, substantially as described.

3. In a fuel-feed governing device, a liquid

fuel pump, variable actuating mechanism 65 for the pump, a pressure actuated governor for said mechanism, a pressure supply device for the governor, a connection leading from said pressure supply device to the intake for the engine to be supplied, and means for 70 periodically opening communication between the governor and the pressure supply device, substantially as described.

4. In a fuel-feed governing device, for internal combustion engines, a liquid fuel 75 pump, variable actuating mechanism for the pump, a pressure actuated governor for said mechanism, a pulsator in communication with the fuel supply for the engine, and a valve for periodically opening communication 80 between the governor and the pulsator, substantially as described.

5. In a fuel-feed governing device for internal combustion engines, a liquid fuel pump, variable actuating mechanism for the 85 pump, a compensating cylinder having a piston therein for determining the position of the actuating mechanism, a compressor having a cylinder with a piston therein, there being a port between the compressor cylinder 90 and the compensating cylinder, a valve in said port connection, and means for opening and closing said valve to equalize the pressure in the compensating cylinder and the compressor cylinder during only a fractional 95 portion of the duration of the operation of compression effected in each compressing stroke of the compressor piston, to equalize the pressure in the governor with that in the pulsator, substantially as described. 100

6. In a fuel-feed governing device for internal combustion engines, a liquid fuel pump, variable actuating mechanism for the pump, a pressure actuated governor for said mechanism, a pulsator for supplying pressure to the governor, said pulsator being in communication with the intake for the engine, a port communicating with the governor and the compensator, a spring-pressed valve in said port arranged to be held in its closed position against the action of the pulsator, and means actuated by the pulsator for opening said valve during only a fractional portion of the duration of the operation of compression effected in each compressing stroke of the compressor piston, substantially as described. 110

7. In a fuel-feed governing device for internal combustion engines, a liquid fuel pump, variable actuating mechanism for said pump, a pressure actuated governor for said mechanism, a pulsator cylinder having a piston therein, means for reciprocating said piston, there being a communication between said cylinder and the fuel supply for the engine, equalizing connections between the cylinder and the governor, there being a plurality of valves in said connection, an auxil- 125

iary pressure chamber between said valves, means for opening one of said valves to equalize the pressure in the pulsator cylinder and the auxiliary chamber during only a 5 fractional portion of the duration of the operation of compression effected in each compressing stroke of the compressor piston, means for closing said valve, means for opening the other valve after the first valve

has been closed to equalize the pressure in 10 the auxiliary chamber and the governor, and means for closing the second valve after the pressure in the governor and auxiliary pressure chamber have been equalized, substantially as described. 15

In testimony whereof I have signed my name to this specification.

LOUIS BENNET HALL.
